CLAIM

The ornamental design for a display mount with non-cylindrical cross supports, as shown and described.

DESCRIPTION

FIG. 1 is a front perspective view of a display mount with non-cylindrical cross supports according to the invention;

FIG. 2 is a rear elevation view of the display mount with non-cylindrical cross supports depicted in FIG. 1;

FIG. 3 is a front elevation view of the display mount with non-cylindrical cross supports depicted in FIG. 1;

FIG. 4 is a bottom plan view of the display mount with non-cylindrical cross supports depicted in FIG. 1;

FIG. 5 is a top plan view of the display mount with non-cylindrical cross supports depicted in FIG. 1;

FIG. 6 is a side elevation view of the display mount with non-cylindrical cross supports depicted in FIG. 1; and,

FIG. 7 is an opposing side elevation view of the display mount with non-cylindrical cross supports depicted in FIG. 1.
